UNITED STATES PATENT OFFICE.

CHARLES G. DIETERICH, OF BROOKLYN, NEW YORK.

HANDLE-BAR FOR BICYCLES.

SPECIFICATION forming part of Letters Patent No. 582,902, dated May 18, 1897.

Application filed June 6, 1896. Serial No. 594,487. (No model.)

To all whom it may concern:

Be it known that I, CHARLES G. DIETERICH, a citizen of Germany, residing at Brooklyn, county of Kings, State of New York, have invented certain new and useful Improvements 5 in Handle-Bars for Bicycles, of which the following is a specification.

This invention relates to certain improvements in the handle-bars of bicycles and other 10 velocipedes by which the cyclist can at any moment raise or lower the handle-bar at will with little effort, so as to lower it for scorching or raise it when he desires to proceed at 15 slower speed; and the invention consists of a handle-bar for bicycles which is so constructed as to turn on its axis in the supporting-sleeve 20 at the upper end of the fork of the front wheel, said sleeve being provided with internal teeth that are engaged by a toothed slide- 25 piece guided in an inclined longitudinal recess of a stationary block supported in the handle-bar against the tension of a cushioning-spring interposed between a shank on the slide-piece and guide-block, said slide-piece being operated by a chain which is connected 30 with one of the handles, which slides on the handle-bar and is locked thereto by a spring-cushioned button, as will be fully described hereinafter and finally pointed out in the 35 claims.

In the accompanying drawings, Figure 1 represents a perspective view of my improved handle-bar for bicycles, partly in section at the end, so as to show the connection with its 40 sliding handle. Fig. 2 is a vertical transverse section on line 2 2, Fig. 1, through the bearing of the handle-bar, said figure being drawn on a larger scale. Fig. 3 is a horizontal longitudinal section on line 3 3, Fig. 1. Fig. 4. is a vertical transverse section through the handle-bar and sliding handle on line 4 4, Fig. 1. Fig. 5 is a detail vertical longitudinal section through the locking device of said handle. Fig. 6 is an enlarged detail horizontal section on line 6 6, Fig. 5; and Fig. 7 is a detail of the outermost end of the handle-bar, showing the slot along which the handle is guided in its sliding motion.

Similar letters of reference indicate corresponding parts.

Referring to the drawings, A represents the

spindle of the front fork; B, a sleeve or bearing that is rigidly attached to the upper end of the spindle A and which is provided with internal teeth b, as shown clearly in Figs. 2 55 and 3. The sleeve B is provided at one end with an inwardly-projecting flange b', which abuts against a shoulder b² of one of the ends of the handle-bar C. The opposite end of the handle-bar C is likewise provided with a shoulder b², against which abuts a ring-shaped screw-nut C², that takes into an interior screw-thread of the sleeve B. About one half of the mid-length handle-bar is cut away nearly for such length as the same is within its 65 sleeve B, as shown in Fig. 2, so as to form a semicircular connecting portion C', against the edges of which abut the lateral shoulders d of a hollow guide-block D, which is arranged in said recessed portion of the handle-bar. 70

The guide-block D is provided with a radial undercut recess D', having an inclined bottom, so as to guide a toothed slide-piece E, which is provided with teeth e at its upper 75 end that intermesh with the internal teeth of the sleeve B, as shown in Figs. 2 and 3.

The guide-block D is prevented from rotating axially by its lateral shoulders d, which 80 abut against the edges of the recessed portion of the handle-bar. The slide-piece is likewise prevented, like the guide-block, from axial rotation, but moves in a longitudinal direction in such a manner that as the same slides along the inclined bottom part of the guide-block 85 its teeth are withdrawn from the teeth of the sleeve B and the slide-piece thereby moved out of engagement with the sleeve, so that the handle-bar can then be turned on its axis in the sleeve in upward or downward direction, 90 as desired.

Longitudinal motion is imparted to the slide-piece E by means of a chain F, that is attached to one end of the slide-piece and conducted through one end of the handle-bar C 95 to the extremity of the same, where it is attached to the end of the sliding handle C³. The opposite end of the slide-piece E is provided with a shank f, that extends into the handle-bar C, said shank being provided with 100 a stop-screw nut f' at its outer end. A helical spring f² is introduced between the nut f'

and a washer f^3 , that is set against the guide-block D, as shown in Fig. 3, so that the tension of the spring f^2 moves the slide-piece toward one end of the guide-block, so that its toothed portion engages with the teeth of the sleeve B. When the handle C³ is moved in outward direction, on releasing a button G, arranged on said handle, the spring f^2 is compressed and the slide-piece moved out of mesh with the sleeve B, whereby the handle-bar is disconnected from the sleeve and permitted to be turned on the axis of the central portion in upward or downward direction. The shank g of the button G is guided in a longitudinal slot G' of the handle-bar and into an interior support g', between which and the handle-bar a helical cushioning-spring g² is interposed, by which the button G' is moved in upward direction into an enlarged opening or socket at the end of slot G' when not depressed by the action of the thumb on the knob G².

When it is desired to adjust the handle-bar, the button G is depressed, so that the sliding handle can slide in outward direction, whereby the slide-piece by the connecting-chain acting thereon is moved against the tension of its cushioning-spring along the guide-block into its drawn position, as shown in dotted lines in Fig. 3, so as to be out of engagement with the sleeve B and permit thereby the turning of the handle-bar until the handle C² is released and returned by the action of the cushioning-spring f^2 into its normal position, in which the button locks the handle in position on the handle-bar and the slide-piece resumes its position in mesh with the internal teeth of the sleeve B, so that the handle-bar is relocked in position.

The adjustment of the handle-bar is of great advantage to cyclists, as it can be lowered when scorching or when racing or against the wind and raised when the cyclist desires to raise up on his wheel and rest for a time.

The adjusting mechanism is easily operated through the sliding motion of the handle by a depression of the button G, and the handle-bar is rigidly locked by the toothed portion of the slide, which intermeshes with the internal teeth of the sleeve. By unscrewing the screw-nut C² the bar can be readily taken out in case any repairs should be necessary, replaced in working position in the sleeve, and retained therein by screwing in the screw-nut.

Having thus described my invention, I

claim as new and desire to secure by Letters Patent—

1. The combination, with an internally-toothed sleeve on the post or spindle of the front fork, of a handle-bar having a recessed portion, a hollow guide-block arranged in and interlocking with said recessed portion, said guide-block being provided with a longitudinal recess open at one side, a slide-piece guided in the recess of said block and having a toothed portion projecting laterally beyond the guide-block, a cushioning-spring for said slide-piece, a chain connected to the slide-piece, and means for pulling the chain so as to move the slide-piece out of engagement with the teeth of the sleeve, and for returning it into engagement therewith for locking the handle-bar in adjusted position, substantially as set forth. 75

2. The combination, with an internally-toothed sleeve or bearing at the upper end of the spindle or post of the front fork, of the handle-bar provided with a recessed middle portion within said sleeve, a recessed guide-block set in said recessed portion and provided with lateral shoulders abutting against the edges of the recessed portion, a slide-piece having a radial toothed portion and guided along the inclined bottom of the guide-block, 80 a shank on the slide-piece, a cushioning-spring interposed between the guide-block and a nut on the shank of said slide-piece, and a chain attached to the slide-piece, said spring and chain being adapted to move the slide-piece 85 into or out of mesh with the teeth of the sleeve, substantially as set forth.

3. The combination of a handle-bar for cycles provided with a longitudinal slot at its outer end, said slot having an enlargement 95 at one end, a sliding handle guided on said handle-bar, an inwardly-projecting support on the handle extending through said slot and into the handle-bar, a spring-cushioned button adapted to enter the enlargement of 100 said slot, the shank of said button being guided in said support on the handle, and a knob exposed through the handle for depressing said button, substantially as set forth.

In testimony that I claim the foregoing as 105 my invention I have signed my name in presence of two subscribing witnesses.

CHARLES G. DIETERICH.
